UNITED STATES PATENT OFFICE

132,623

DESIGN FOR A PICTURE FRAME

Carl E. Knutson, Chicago, Ill.

Application December 24, 1941, Serial No. 104,833

Term of patent 7 years

To all whom it may concern:

Be it known that I, Carl E. Knutson, a citizen of the United States of America, residing at 6503 Raven Street, Chicago, Illinois, have invented a new, original, and ornamental Design for a Picture Frame, of which the following is a specification, reference being had to the accompanying drawing, forming a part thereof. Fig. 1 is a face view of my picture frame in closed position; Fig. 2 is a side elevational view of the

same; Fig. 3 is a rear view; Fig. 4 is a front elevational view in open position; Fig. 5 is a rear elevational view in open position on a reduced scale; and Fig. 6 is a bottom view on a reduced scale.

I claim:

The ornamental design for a picture frame, substantially as shown.

CARL E. KNUTSON.
